[57] CLAIM

The ornamental design for a beaded bag cover, as shown and described.

DESCRIPTION

FIG. 1 is a perspective view of the preferred embodiment of my new beaded bag cover with beaded strap;
FIG. 2 is a front view thereof;
FIG. 3 is a left side view thereof;
FIG. 4 is a right side view thereof;
FIG. 5 is a back view thereof;
FIG. 6 is a top view thereof;
FIG. 7 is a bottom view thereof;
FIG. 8 is a front view thereof, with front flap open. The back of the front flap is not shown for clarity of illustration;
FIG. 9 is a front view of a second embodiment of my new beaded bag cover;
FIG. 10 is a left side view thereof;
FIG. 11 is a right side view thereof;
FIG. 12 is a front view of a third embodiment of my new beaded bag cover;
FIG. 13 is a left side view thereof; and,
FIG. 14 is a right side view thereof.
The broken line showing of a purse inside of the beaded bag cover is for illustrative purposes only and forms no part of the claim.
